CHAIR FOR REVERSE SITTING

Nolon M. Doss, Sr., P.O. Box 14375,
Phoenix, Ariz. 85031

Filed Oct. 1, 1965, Ser. No. 87,284

Term of patent 14 years

(Cl. D15—1)

FIG. 1 is a perspective view of a chair for reverse sitting showing my design.

FIG. 2 is a rear elevation of the chair.

FIG. 3 is a side elevation of the chair.

I claim:

The ornamental design for a chair for reverse sitting as shown.
